ATTORNEYS

UNITED STATES PATENT OFFICE.

LOUIS SANDERS, OF BROOKLYN, NEW YORK.

DESIGN FOR A BELT-BUCKLE.

SPECIFICATION forming part of Design No. 20,048, dated July 22, 1890.

Application filed May 28, 1890. Serial No. 353,498. Term of patent 14 years.

To all whom it may concern:

Be it known that I, LOUIS SANDERS, a citizen of the United States, residing at Brooklyn, in the county of Kings and State of New York, 5 have invented and produced a new and original Design for Buckles, of which the following is a specification, reference being had to the accompanying drawing, forming part thereof, which represents a front elevation of my de-

sign.

The design consists of the representation of two link-like figures A, represented as connected, two crossed racquet-like figures B, and a

bar-like figure C between the link figures and represented as intersecting the racquet-like 15 figures. Lines D, representing a chain, are drawn from the racquet-like figures to one of the link-like figures, and ball-like figures D' are represented upon the racquet-like figures.

I claim—

A design for the belt-buckle, substantially as shown and described.

LOUIS SANDERS.
